UNITED STATES PATENT OFFICE.

JOHN JEFFESON DOUGHTY, OF LAKE CITY, MINNESOTA.

DEVICE FOR STRETCHING AND TIGHTENING ELEVATOR-BELTS.

SPECIFICATION forming part of Letters Patent No. 390,213, dated October 2, 1888.

Application filed July 10, 1888. Serial No. 279,503. (No model.)

To all whom it may concern:

Be it known that I, JOHN JEFFESON DOUGHTY, a citizen of the United States, residing at Lake City, in the county of Wabasha and State of Minnesota, have invented certain new and useful Improvements in Devices for Stretching and Tightening either New or Old Elevator-Belts; and I do hereby declare the following to be a full, clear, and exact description of the invention, such as will enable others skilled in the art to which it appertains to make and use the same.

This invention relates to improvements in that class of devices known as "elevator-belt stretchers and tighteners," and has for its object to hold, stretch into position, and tighten the free or meeting ends of the belt, thus taking up the slack which is the result of the continued use of the belt preparatory to lacing the meeting ends together.

To this end the invention consists in the novel construction and arrangement of the several parts, as will be hereinafter fully described, and pointed out in the claims.

In the accompanying drawings, which fully illustrate my invention, and to which reference is had, Figure 1 is a front elevation of the elevator-leg, showing a part of one side of the leg and the door removed to show the application of the stretching and tightening devices, and also elevator-belt with attached buckets. Fig. 2 is a side sectional elevation of the same, and Fig. 3 is a perspective view of the clevis.

Similar letters of reference indicate similar parts throughout all the figures.

Referring to the drawings, A represents a section of an elevator-leg, through which is passed and inclosed therein an elevator-belt, X, having secured in any suitable manner thereon elevator-buckets y, which will be hereinafter more particularly referred to.

B is a metallic base or bearing plate, which is detachably secured to the forward and lower part of the elevator-leg section by means of a right-angular integrally-constructed flange, which passes over the upper part of the inclosed and lower portion of the leg-section. The lower portion of this base or bearing plate B has another flange, b', integrally constructed thereon and turned at a right angle to B in

the opposite direction to that of the upper flange, and has a perforation in the center thereof, through which is passed an adjusting-screw, h, the upper end of which bears in a depression upon the under side of an integrally-constructed flange, f', turned at right angles upon the lower end of a vertical adjustable T-shaped slide or tightener, b, slotted as at b', said flange being parallel with the flange b' upon the lower part of the bearing-plate B. The upper part of this tightener b forms the fulcrum for a tightening and stretching lever, d, which rests at an angle of about thirty degrees thereon, and the lower or downwardly-inclined end of this lever, which bears against the belt in the leg section, is beveled off at a slight angle, as at d', so that it can get a good purchase or grip upon the belt when the longer and outer end of the lever d is depressed, as more clearly seen in Fig. 2 of the drawings. This tightener b is secured to the base or bearing plate B, and held in position relatively thereto by means of a screw-bolt, g, which is screwed into the plate B and guide-piece g', by which it is guided (that is, the tightener or slotted slide) in its vertical adjustment upon the base or bearing plate B, to raise or lower the end of the lever d in conjunction with the adjusting-screw h, which passes through the flange b' of the bearing-plate B and bears against the under side of the flange f' of the tightener or slide previously described.

Secured to or near the center of lever d is one end of a chain, k, secured to the flange b' by means of a hook, k', and by which the lever d is held in its operative position.

C is a projecting metal plate or fastening slotted upon its under side and detachably secured to the forward and upper part of the elevator-leg section by means of supporting-pins driven into the elevator-leg section and flanges C' C'', integrally constructed with the plate or fastening C.

To one of the ends of the plate C is pivotally secured one end of a latch-bar, i, having a perforation in its opposite end, which registers with a perforation in the under side of the other end of the plate or fastening C, through which is passed a thumb-screw, i', which locks and unlocks in place the latch-bar i', which supports and holds in place the ele-

vator-belt holding or tightening fork *e*, this fork having tines *e'* secured to one of its ends, which stick into or through the belt and tighten it to form a junction with that end of the belt operated upon by the bevel end of the lever *d*, as clearly shown in Fig. 2 of the drawings. These tightening and stretching devices *B C*, with the fork and lever, being detachably secured to the elevator-leg section, 10 can be readily removed when not in use and as readily applied when it becomes necessary to use them.

In Fig. 3 is shown a clevis, *L*, composed of the bar *l*, having teeth *l'* thereon for engagement with the rear side of the bucket-belt. From the bar *l* extend parallel arms which terminate in hooks *l' l''*, for engagement with the journals *j* on the plate *j* of lever *d*. In use the clevis is placed behind the belt at or near the point of severance, the teeth resting against the belt ready to enter the same when power is applied to the lever through the screw *h*. The hooks, it will be perceived, extend over and engage with the journals, as stated above. 25 When the belt is severed and the operation begins, as described below, the teeth are forced into the leather to prevent its slipping, while the hooks, in connection with the journals, serve to bind the belt tightly to the lever. The 30 greater the power applied to the screw *h* the firmer will be the grasp of the clevis upon its end of the belt.

The operation of my device will be obvious when taken in connection with the accompanying drawings, but may herein be briefly rehearsed as follows: To stretch or tighten the belt, apply the upper metallic plate or fastening to the elevator-leg section, with the supporting-pins underneath for supporting and 40 holding it in place; then unscrew the thumb-screw in the latch bar and turn the bar back upon its pivot; insert the forked lever through the slot in the plate or fastening and elevator-leg section until the tines of the forked lever 45 pierce and fasten themselves into or through the belt, care being taken to have the tines of the forked lever far enough up on the belt so that the lever will draw upon the belt when it is put in its place in the plate or fastening, after which 50 fasten or lock the latch-bar in its place. The lower tightener is applied to the elevator-leg section with the fulcrum down to its lowest position, and the lever is then applied with its outer end elevated to an angle of about

thirty degrees. The connection is made with the belt by the tines of the forked lever in the upper plate or fastening or with the clevis. The fastening being thus made, bring the lever down to a horizontal position and fasten it with the chain. Then turn up the tightener by 55 means of the adjusting-screw until the belt is tight enough or the lever stands at an angle of about thirty degrees. If the belt is not properly stretched or tightened at this point, drop the lever down to a horizontal position, fasten it with the chain, and turn up again by means of the adjusting-screw, and so on, until the belt is properly stretched or tightened.

Having thus described my invention, what I claim as new, and desire to secure by Letters 70 Patent, is—

1. In a belt stretcher and tightener, the combination of the forked lever, a flanged plate secured to the elevator-leg and provided with a slot and set-screw for securing the said lever thereto, and a lever for stretching the end of the belt toward the forked lever, substantially as described.

2. In a belt stretcher and tightener, the combination of the forked lever, a flanged plate secured to the elevator-leg and provided with a slot and set-screw for securing the said lever thereto, and a lever for stretching the end of the belt toward the forked lever and an adjustable tightener for said lever, and means 85 for securing said lever in its adjusted position, substantially as described.

3. In a belt stretcher and tightener, the combination of the forked lever, a flanged plate secured to the elevator-leg and provided with a slot and set-screw for securing the said lever thereto, a lever for stretching the end of the belt toward the forked lever, an adjustable tightener for said lever, means for securing 90 said lever in its adjusted position, a clevis detachably secured to the stretching-lever for gripping the belt in stretching, a base-plate secured to the elevator-leg, an adjustable tightener secured to the base-plate by means of a bolt, and an adjusting-screw for adjusting the 95 tightener, substantially as described, and for the purpose set forth.

In testimony whereof I affix my signature in presence of two witnesses.

JOHN JEFFESON DOUGHTY.
